[57] CLAIM

The ornamental design for an electrical tester, as shown and described.

DESCRIPTION

FIG. 1 is a perspective view of an electrical tester showing my new design;

FIG. 2 is a front plan view;

FIG. 3 is a right side elevational view;

FIG. 4 is a left side elevational view;

FIG. 5 is a rear plan view;

FIG. 6 is a top elevational view; and,

FIG. 7 is a bottom elevational view.

The broken line showing is for illustrative purposes only and forms no part of the claimed design.
